UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 17,754, dated September 27, 1887.

Application filed August 8, 1887. Serial No. 246,463. Term of patent 3½ years.

To all whom it may concern:

Be it known that I, MARY TURNER, of the city, county, and State of New York, have invented and produced a new and original Design for a Pattern of a Miss's Costume; and I do hereby declare that the engraved prints accompanying this specification convey to any one accustomed to using paper patterns a clear understanding of how a garment made up by the pattern will appear.

The design shows a round walking-skirt and a basque. The skirt displays a long oval front drapery exhibiting draping plaits in its side edges, and a full back drapery that displays plaits at the top and falls in two points nearly to the edge. The basque exhibits close fitting fronts displaying a side-plaited ornament at each side of the closing above the bust, revers

turning backward from the plaited ornaments, and a bodice section describing a point at the center of the top and bottom, and at each side button-holes and buttons; a close fitting back exhibiting an underfolded double box-plait at the end of the center seam, and small revers at the front edges of the back skirt, coat sleeves, and a standing collar.

What I claim as my invention, and desire to secure by Letters Patent, is—

The design for a miss's costume, as shown in the engraved print accompanying this specification.

MARY TURNER.
